CLAIM

The ornamental design for a front panel assembly for a portable hemodialysis system, as shown and described.

DESCRIPTION

FIG. 1 is a front, elevational view of a front panel assembly, in its environment, for a portable hemodialysis system;

FIG. 2 is an enlarged view of a portion of FIG. 1;

FIG. 3 is a front, left side perspective view of a front panel assembly, in its environment, for a portable hemodialysis system;

FIG. 4 is an enlarged view of a portion of FIG. 2;

FIG. 5 is a front, right side perspective view of a front panel assembly, in its environment, for a portable hemodialysis system;

FIG. 6 is an enlarged view of a portion of FIG. 3;

FIG. 7 is a left side elevational view of a front panel assembly, in its environment, for a portable hemodialysis system;

FIG. 8 is an enlarged view of a portion of FIG. 4;

FIG. 9 is a right side elevational view of a front panel assembly, in its environment, for a portable hemodialysis system;

FIG. 10 is an enlarged view of a portion of FIG. 5;

FIG. 11 is a top plan view, the bottom view being plain need not be considered, of a front panel assembly, in its environment, for a portable hemodialysis system; and,

FIG. 12 is an enlarged view of a portion of FIG. 6.

The broken lines illustrate environmental structure and portions of the front panel assembly for a portable hemodialysis system which form no part of the claimed design.
